UNITED STATES PATENT OFFICE.

HARRY H. LABADIE AND BURTON B. BEERS, OF CHICAGO, ILLINOIS, ASSIGNEES, BY
DIRECT AND MESNE ASSIGNMENTS, OF ONE-HALF TO SAID LABADIE AND ONE-HALF
TO THE ESTATE OF WILLIAM SCHWEITZER, DECEASED.

COMBINED LUNCHEON AND CARRYING CASE.

1,220,159.

Specification of Letters Patent. Patented Mar. 20, 1917.

Application filed August 18, 1916. Serial No. 115,671.

To all whom it may concern:

Be it known that we, HARRY H. LABADIE and BURTON B. BEERS, citizens of the United States, residents of Chicago, in the county 5 of Cook and State of Illinois, have jointly invented certain new and useful Improvements in a Combined Luncheon and Carrying Case; and we do hereby declare that the following description of our said invention, 10 taken in connection with the accompanying sheets of drawings, form a full, clear, and exact specification, which will enable others skilled in the art to which our said invention appertains to make and use the same.

15 The object of this invention is the production of a very efficient and serviceable luncheon and carrying case, which, when not in use as a luncheon case, may be readily converted into a suit, or other carrying case. 20 While this case has been designed particularly for use in an automobile, for carrying lunch for the occupants thereof, it is, however, capable of being used for other, analogous purposes, such as carrying lunch for 25 picnic parties, excursions, etc.

In the drawings already referred to, which serve to illustrate our invention more fully, and which form a part of this specification, Figure 1 is a sectional elevation on line 1—1, 30 of Fig. 2. Fig. 2 is a plan of the case in open condition. Fig. 3 is a sectional elevation on line 3—3 of Fig. 2, the parts contained in the luncheon case having been removed to show the condition of the case 35 when suitable for a suit case.

A, in these drawings designates the lower part of the carrying case, and B, the upper part or cover for the same, these two parts being hinged to each other by hinges 12, in 40 any convenient manner. The lower section of this carrying case is rabbeted along its upper edge, as at 13, and the upper section or cover has its lower edges 14, constructed to engage said rabbets, thereby affording a 45 closed joint at the adjacent parts and preventing dust from entering the case when in closed condition. A suitable lock 15, is provided for on the lower section A, and a coacting catch 16, on the cover B, afford 50 means for locking the case, while a suitable handle or grip 17, enables the case being conveniently carried about.

In the lower section A, and to the inner side of the front wall 18, and also to the

inner side of the rear wall 19, if desired, 55 there are provided, preferably metallic, cleats 20, the object of which will herein-after appear. In this lower section there are removably placed a series of containers, comprising a number of thermos bottles C, 60 and a multiplicity of, preferably rectangular, metallic boxes D, the former for carrying a supply of liquid refreshments, and the latter for containing sandwiches and other food. Each of these boxes has a handle 65 24, for convenience in lifting the boxes out 70 of the case, and in handling them, and a catch 25, whereby the lids 26 of said boxes may be locked thereto. These boxes are preferably made from sheet metal, and of a length and depth corresponding to the 75 width and the depth of the lower section A; and they are of a width to fit nicely between the cleats 20, whereby said boxes are retained in proper position, it being understood that the length of the section A is 80 equal to the aggregate of the widths of said boxes plus the total of the diameters of the thermos bottles C, so that these parts fit snugly into the lower section, and are, thereby, prevented from shifting and rattling 85 when the case is carried about.

In the cover section B, there is located a pad, tray or pan E. This pan is removably secured to the interior of said cover by suitable fastenings 27, preferably of the snap-button variety; and in this pan there are provided a series of loops 28, wherein are removably retained a number of forks F, spoons G, and knives H. These loops are preferably formed by a tape or webbing 29, which webbing is stitched to the bottom of the pan E, at its ends, as at 30, and intermediate stitches 31, all as clearly indicated in Fig. 1. In the pan E there are further tapes, 32, 33, the former being, as it were, 90 loops, while the latter tapes comprise two sections, overlapping each other at their ends, where a suitable fastening 34, preferably a snap-button, connects these two ends. In the loops 32 there are held a number of 95 superposed plates, which plates are retained in position by the cross tapes but may be removed therefrom by unfastening the tapes 100 105.

33. And underneath these cross tapes there are placed a series of napkins J.

Further loops 35, are suitably placed in the tray E, wherein are retained receptacles K, containing condiments, spices, or seasonings.

As shown, the table service of knives, forks, and spoons, etc., are arranged for a party of six or more persons; but we do not wish to confine ourselves to this precise arrangement. For instance, we may dispense with one of the boxes D, and some of the thermos bottles C, and a corresponding number of the knives, forks, and spoons, etc., and reduce the size of the carrying case accordingly; or we may increase the size of the latter and supply the same with additional conveniences to supply a greater number of persons, a matter which will readily suggest itself to a person conversant with the requirements or wishes of customers desiring to purchase an outfit, such as described.

We have already stated that all the parts contained in the two sections A, B, of the carrying case are removably retained therein so that, when the case is not required for carrying a lunch, all of these parts may be removed therefrom, when the case, as shown in Fig. 3, is capable of being used for many other purposes, such as a suit case, a sample case, and the like, without change or modification of any kind.

To strengthen the case, it is provided with the usual corner stiffeners 37, on both, the bottom and the top sections, and to further strengthen the bottom sections, we fasten, preferably metallic angles 38, adjacent the rabbets 13, as best illustrated in Fig. 3. And, in order to sustain the cover B in substantially vertical position when the case is open, we provide at the ends of the case, preferably flexible, links 39, one of their ends being fastened to the section A at 40, and the other ends being secured to the cover B, at 41. These links, being flexible, and preferably made from webbing, will readily fold into the case when the cover is being closed, and thereby be entirely out of the way.

As shown, the case contains two of the boxes and three of the thermos bottles; but this arrangement can be varied by having

one, thermos bottle located between two boxes, or two thermos bottles at the sides of one box, to reduce the size of the carrying case, while the number of boxes and thermos bottles may be increased over that shown, without departing from the scope of our invention.

While we have hereinbefore described the preferred embodiment of our invention, we desire it to be understood that we are aware that some of the details of construction may be varied, and some parts omitted without departing from the scope of our invention as defined in the subjoined claim.

Having thus fully described our invention, we claim as new, and desire to secure by Letters Patent of the United States—

A combined luncheon and carrying case, including an upper, and a lower section, said sections being hinged to each other, there being in said lower section a series of vertically disposed cleats, a multiplicity of boxes in said lower section, each of said boxes having a hinged cover, a handle on said cover, and a catch on said box to hold said cover in closed condition, said boxes being retained in spaced relationship between said cleats, a thermos bottle between adjacent boxes, and two additional thermos bottles, one at each end of said lower section, said thermos bottle being retained in horizontal position by said boxes, said boxes and said thermos bottle being of a length substantially equal to the width of said lower section and a tray in the upper section, said tray being removably retained in the latter section, there being in said tray a series of loops in closely spaced relationship, said loops being constructed to removably retainable cutlery, and further loops above the first mentioned loops constructed to retain circular plates, the latter loops comprising each a horizontal member fixed at both ends to said tray, and two coacting vertical members, the latter members being secured at overlapping ends by a separable fastening, said upper section being retained in vertical position by flexible links.

In testimony that we claim the foregoing as our joint invention, we have hereunto set our hands, at Chicago, Ill.

HARRY H. LABADIE.
BURTON B. BEERS.
